UNITED STATES PATENT OFFICE

2,635,812

TRANSFER MECHANISM FOR CALCULATING MACHINES

Thomas O. Mehan, Park Ridge, Ill., assignor to
Victor Adding Machine Co., Chicago, Ill., a
corporation of Illinois

Application July 15, 1946, Serial No. 683,804, now
Patent No. 2,475,510, dated July 5, 1949, which
is a division of application Serial No. 282,787,
July 4, 1939. Divided and this application February 8, 1949, Serial No. 75,244

4 Claims. (Cl. 235—137)

1

My invention relates generally to calculating machines, and more particularly to improved transfer or tens carryover mechanism for machines of this type.

In most adding machines, it is necessary to take a blank stroke of the operating handle (or drive the machine through one cycle if it is electrically operated), in order to reset the accumulator transfer mechanism for operation upon the following cycle, and it is one of the objects of the present invention to provide a simple and effective control means for automatically resetting the transfer mechanism upon the initial portion of an operating cycle prior to the time the racks have been moved from their normal or rest positions.

A further object is to provide an improved means for restoring the accumulator tens transfer mechanism to normal position, which is rapid in operation, and simple in construction.

Other objects will appear from the following description, reference being had to the accompanying drawings, in which:

Fig. 1 is a fragmentary longitudinal vertical sectional view, looking toward the left, of the adding machine, showing particularly the transfer mechanism and the means for resetting the same; and

Fig. 2 is an enlarged longitudinal sectional view, showing the means by which the transfer mechanism is quickly reset during the initial portion of an operating cycle.

This application is a division of my copending application Serial No. 683,804, filed July 15, 1946, which has matured into Patent No. 2,475,510, and which was a division of my now abandoned application Serial No. 282,787, filed July 4, 1939.

Referring to Fig. 1, the adding machine is provided with a keyboard comprising a plurality of numeral keys 10 having stems 11 guided for vertical movement in slots formed in plates 12 and 14. Each of the key stems 11 is provided with a cam projection 16 and a notch 18 for cooperation with a longitudinally slidable latch bar 20 and a similarly movable actuator release bar 22, there being one bar 20 and one bar 22 for each longitudinal row of keys. The bars 20 are notched to provide shoulders 24 for engagement with the cam projections 16, alternate shoulders 24 being on opposite edges of the bars 20. Similarly, shoulders 25 for engagement with the cam surfaces of the projections 16 on the key stems are provided on the actuator release bar 22.

The bars 20 and 22 are resiliently held in their rearward positions by suitable springs, such as

2

the spring 21 shown in Fig. 1, for holding one of the latching bars 20 in its rearward position. When one of the keys 10 is depressed, its camming projection 16 successively cams the bars 20 and 22 forwardly until the projection 16 of the key stem passes beneath the latching bar 20, whereupon the spring operating the latter will move it into the notch 18 and thereby latch the key in depressed position in the customary manner. The strokes of the keys are limited by fixed rods 23, each of which passes through elongated slots 24' in the key stems 11 of a transverse row. The keys, when released by the latch bars 20, are returned to their normal positions by coil springs 26 which extend through suitable openings in the key stems 11 of a transverse row, are suitably anchored at their ends, and are supported intermediate longitudinal rows of keys by vertical separator plates 27 which also serve to join plates 12 and 14.

In a normal adding operation of the machine, the lower ends of such of the key stems 11 as have been depressed, are adapted to form stops to limit the rearward travel of actuator slides 30 which are suitably guided for longitudinal movement and may be drawn rearwardly by springs 32 in the customary manner after the slides have been released.

It will be understood that there is a slide 30 for each denominational order of the numeral keys 10, each of these slides being connected by a plate 34 with an actuator 36, the actuators being mounted for longitudinal travel on a pair of rods 38, 39 which extend through elongated slots 40 and 41, respectively, formed in the actuator, the actuators being suitably guided and spaced by combs 42 and 43. The actuator 36 for the highest denominational order is not connected to a slide and is therefore provided with a tension spring 44 for drawing it rearwardly (as will appear hereinafter) when a total or subtotal is taken.

The rearward end of each of the actuators 36 is provided with a rack 46 which is in mesh with a segmental pinion 48 formed on a type sector 50, the type sector having a row of type 52 bearing the type characters from "0" to "9" thereon.

The type segments 50 are mounted for rotation on a shaft 54 and adjacent each of these segments there is provided a sector gear 60, the teeth of which are adapted for engagement with accumulator pinions 66 mounted for rotation upon a shaft 68. Each of the segments 50 is connected to its associated gear 60 by a tension spring 56, the extent of relative movement of these parts

under the influence of the spring being limited by the engagement of a sidewardly extending lug 57 on the segment 50 with the portion 58 of the gear 60. The shaft 68 is secured at its ends to a pair of similar arms 70 pivoted on a rod 72 so that the accumulator pinions 66 may be swung into and out of engagement with the teeth of the gear sector 60. Each of the accumulator pinions has secured thereto a disc provided with a transfer cam tooth 74 and a disc 76 having a notch 77. The arms 70 are joined by a comb strip 80. The accumulator pinions 66, when in the normal position shown in Fig. 1, are held from accidental rotation by a toothed strip 82 rigidly secured to the vertical frame plates 83 and 85 of the machine.

A comb plate 84, likewise rigidly secured to the frame plates, forms guides for transfer pawls 86, pivoted on rod 87, and for pawl latches 88, pivoted on a rod 89. Springs 90 bias both the pawls 86 and their latches 88 for clockwise rotation. At the rearward end of each transfer pawl 86 there is a projection 92 for engagement with its associated transfer cam tooth 74, a notch 95, and a stop projection 93 for engagement with a lug 94 punched and bent sidewardly from the sector gear 60 of the next higher denominational order. Thus when a transfer pawl 86 is tripped, spring 56 rotates the gear sector clockwise a distance sufficient to cause its associated pinion 66 to be rotated through one-tenth of a revolution, thereby to effect the transfer or carry-over. A pawl 86 which has been tripped is held in tripped position by its latch 88, which swings clockwise when the pawl is tripped. Such movement is permitted since the comb 80 is raised when the accumulator pinions 66 are in mesh with the gear sectors 60.

The latches 88 are restored to normal position by the comb 80 as the accumulator arms 70 are returned to normal position. A pawl 86 which has been tripped is held in tripped position by the lug 94 which then rests in the notch 95. The tripped pawls are permitted to return to normal position during the initial portion of the following cycle of operation by a plate 98 secured to a shaft 100. When the shaft 100 is rotated clockwise the plate 98 engages a projection 101 on each of the gear sectors 60 which has been operated to effect a transfer and rotates it counterclockwise sufficiently to withdraw its lug 94 from the notch 95 of the transfer pawl 86, so that the latter may be swung back to its normal position by its spring 90.

The shaft 100 is rotated clockwise by the mechanism best shown in Fig. 2. The shaft 100 has an arm 102 secured thereto, and this arm has a wipe pawl 104 pivotally secured thereto by a shouldered rivet 106, the pawl being held in the position shown in Fig. 2 by a tension spring 108. The main operating shaft 110 has a plate 112 rigidly secured thereto and the rearwardly extending finger of the wipe pawl 104 normally rests on a stud 114 which projects sidewardly from the plate 112. Thus during the initial portion of an operating cycle, as the main shaft 110 is rotated counterclockwise the stud 114 engages in the notch 116 of the wipe pawl 104, and swings the pawl clockwise, thereby, through a toggle-like action, moving the arm 102 and the shaft 100 clockwise. As soon as the stud 114 wipes past the pawl 104, the arm 102 and shaft 100 are returned to normal position by a spring 118 (Fig. 1), the return movement being limited by the engagement of the rearward end of arm 102 with

a fixed stud 120. Near the end of the operating cycle the stud 114 wipes freely past the pawl 104.

A restoring bail rod 122 extends through arcuate slots 124 formed in all of the type segments 50 and through similar slots 123 formed in the frame plates 83 and 85, respectively. This bail rod 122 is swung counterclockwise shortly after the commencement of the operating cycle to permit the actuators to move rearwardly under the influence of their springs 32 and 44, and is swung clockwise after printing has been effected and near the end of the operating cycle, to a position in which the rod 122 is shown in Fig. 2, thus restoring the type segments 50, together with the actuators 36 and slides 38, to normal position. Mechanism for accomplishing this is common in the art, as shown, for example, in my Patent No. 2,411,050.

From the foregoing, it will appear that as the main shaft 110 commences its forward (counterclockwise, Fig. 2) oscillatory stroke, the stud 114, by its engagement with the wipe pawl 104 will, through a toggle-like action, swing the lever 102 clockwise very rapidly to rotate the shaft 100 clockwise so that the plate 98, by its engagement with the projections 101 on each of the gear sectors 60 which has been operated to cause a transfer, rotates it counterclockwise sufficiently to permit the resetting of the transfer pawls to their normal positions under the influence of their springs 90. This movement of the plate 98 is very rapid, because as soon as the stud 114 wipes past the pawl 104, the spring 118 will return the plate to its normal position so that the gear sectors 60 are again free to effect transfer operations.

Since all of the above operations take place prior to the time that the actuators 36 are permitted to move rearwardly, that is, before they are freed for movement by the counterclockwise swinging movement of the restoring bail 122, and before the accumulator pinions are enmeshed, a total-taking operation may be effected without the necessity of preceding it with a blank stroke, as is necessary in many prior machines, in order to restore their transfer mechanisms.

While I have shown and described a particular embodiment of my invention, it will be apparent that numerous variations and modifications thereof may be made without departing from the underlying principles of the invention. I therefore desire, by the following claims, to include within the scope of the invention all such variations and modifications by which substantially the results of my invention may be obtained through the use of substantially the same or equivalent means.

I claim:

1. In a calculating machine, the combination of an accumulator comprising a plurality of independently rotatable pinions, a transfer cam connected to each of the pinions, a transfer mechanism associated with each of the cams and operable by the cams to effect transfers to the pinions of the next higher denominational order, said transfer mechanism including a normally latched resiliently operated actuator tripped by the cam to operate the pinion into which the transfer is effected, a general operator, a part common to all of the actuators and operable to reset actuators which have been tripped, a wipe pawl mechanism connected between the general operator and the part to operate the latter in one direction during the initial portion only of

the operating cycle of the machine, and a spring to move the part in the opposite direction.

2. In a calculating machine having a plurality of settable amount representing stops; actuators cooperable with the stops to be differentially set thereby; toothed elements having lost motion connections with the actuators respectively, permitting the toothed elements to move to the extent of one tooth thereof relative to their actuators; resilient means for causing such movement of the elements with respect to their actuators; accumulator pinions respectively engageable with the toothed elements; transfer cams on the accumulator pinions; transfer pawls cooperable with the cams respectively and having parts engageable with the toothed elements respectively to hold the latter in normal positions against movement by their associated actuators and thereby cause lost motion of the elements with respect to their actuators as the actuators move to their normal positions; latches to hold the transfer pawls in operated position; a main shaft; means operated by the main shaft to cause engagement of the accumulator pinions with the elements shortly after the commencement of an operating cycle of the machine upon total taking operations; a restoring part movable to and fro mechanism operated by the main shaft prior to the engagement of the accumulator pinions with the toothed elements to move the restoring part in a direction to restore any toothed elements which have been operated to effect a transfer, and resilient means for moving the restoring part in the opposite direction.

3. In a calculating machine having a plurality of settable amount representing stops; actuators movable from their normal positions to engage the stops and to be differentially set thereby; toothed elements having lost motion connections with the actuators respectively, permitting the toothed elements to move to the extent of one tooth thereof relative to their actuators; a restoring bail operated near the end of a machine cycle to restore the actuators to their normal positions; resilient means between the toothed elements and actuators to take up the lost motion; accumulator pinions respectively engageable with the toothed elements; trans-

fer cams on the accumulator pinions; transfer pawls cooperable with the cams respectively and having parts engageable with the toothed elements respectively to arrest movement of the toothed elements and thereby to cause motion of the toothed elements with respect to their actuators as the actuators are restored to normal position by the restoring bail; a general operator; means operated by the general operator to cause engagement of the accumulator pinions with the toothed elements shortly after the commencement of a total-taking operating cycle of the machine; a restoring bar movable to and fro and engageable with such of the toothed elements as have effected transfers to move them a sufficient distance to permit resetting of their transfer pawls; and mechanism actuated by the general operator to move the restoring bar to and fro during the initial portion only of each operating cycle and prior to the engagement of the accumulator pinions with the toothed elements.

4. In a calculating machine, an accumulator, a spring, actuating and transfer mechanism for the accumulator having a part which is moved from its normal position by power stored in said spring when a transfer is effected, a main operator, means operated thereby to cause engagement of the accumulator with said part of said mechanism during total taking operations shortly after the beginning of an operating cycle, a member engageable with said part of said mechanism to restore said part and the transfer mechanism to normal position, a spring biasing said member to normal position, and a wipe pawl mechanism driven by the main operator to move said member against the force of its biasing spring prior to the engagement of said part with the accumulator, thereby to restore said part and said transfer mechanism to normal position.

THOMAS O. MEHAN.
